UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

MULTIPRESSURE REGULATOR.

Application filed September 19, 1927. Serial No. 220,361.

This invention relates to compressors, but more particularly to a pressure regulator adapted to operate at different pressures in the receiver tank for controlling the communication between the compressor cylinder and the intake supply.

One object of the invention is to enable automatic unloading of the compressor cylinder at different pressures in the receiver tank and thus hold the pressure in the receiver tank between a maximum and a minimum predetermined value.

Another object is to assure a supply of pressure fluid at maximum pressure for overcoming the inertia of the element intended to be actuated thereby and after such element has been set in operation to supply pressure fluid thereto of lower value sufficient to assure continued operation and at the same time to actuate the unloading element of the compressor with the reduced operating pressure and thus maintain the receiver pressure substantially at the desired operating pressure.

Other objects will be in part obvious and in part pointed out hereinafter.

The invention consists of the combination of elements and arrangement of parts having the general mode of operation substantially as hereinafter described and claimed and illustrated in the accompanying drawings, in which

The figure is a diagrammatic illustration partly in section of a compressor system having the invention applied thereto.

Referring to the drawings, A designates a compressor cylinder having an inlet opening B and a discharge opening C. The cylinder A is provided with the usual inlet valves D which control communication between the inlet opening B and the compression chamber E. Between the compression chamber E and the discharge opening C is disposed the usual discharge valve F for controlling communication between these elements.

In the present instance an intake unloader valve G is disposed over the inlet opening B to control the intake supply to the cylinder A. The unloaded valve G illustrated is of a well known type comprising a casing H in which is disposed slidably a valve J for controlling the admission ports K and L in the casing H. The valve J is normally

held open by a spring O which may be provided with suitable adjusting means, as for instance, a screw P for regulating the tension of said spring O.

Connected to the discharge opening C is a pipe Q through which pressure fluid compressed in the compression chamber E may be conveyed to a receiver tank R.

In certain lines of work employing pressure fluid, it is essential that pressure fluid of a high value be available for overcoming the inertia of the element or material intended to be actuated thereby and after such element has been set in action that its constant actuation at a satisfactory speed be maintained at a lower pressure. This is particularly the case in devices for feeding fuel, such as pulverized coal, through a nozzle into the burner or kiln to which the fuel is being supplied.

In order to meet both of these requirements, means are provided for unloading the compressor, either when it is desired to maintain the maximum pressure in the receiver R or the minimum pressure. These means in the present instance comprise a casing S having a pair of valve chambers T and U which communicate with an intermediate chamber V in the casing S through ports W for admitting pressure fluid from the valve chambers T and U into a cylinder X forming an integral part of the intake unloader valve H, and in which cylinder X is disposed a piston Y adapted to be pressed against the valve J by pressure fluid for closing said valve J. The piston Y is provided with an aperture Z to permit the gradual exhaust of pressure fluid from the cylinder X through the piston Y and thence through an aperture b in the valve J to the atmosphere.

Disposed in the valve chamber T is a valve c for controlling the aperture W. The valve c may be in the form of a needle valve and may be attached at its rearward end in any suitable manner to a diaphragm d clamped between the casing S and a cup shaped cover e in which is disposed a spring f. The spring f may be calibrated to withstand all pressures below the maximum pressure which it is desired to maintain in the receiver tank R. In this instance the spring seats directly on the diaphragm d with one end and with its other end against a spring

plug *g* which in turn bears against a set screw *h* in the cover *e* whereby the tension of the spring *f* may be regulated. Preferably, the inner surface of the diaphragm *d* is constantly exposed to pressure fluid from the receiver *R* and such pressure fluid is conveyed to the chamber *T* through a pipe *j* leading from the receiver tank *R*.

Similar means are provided for closing the valve *J* at a minimum pressure in the receiver tank *R* or, in other words, that minimum pressure at which the element to be actuated may be kept in operation after the initial introduction of the maximum pressure to the work. These means accordingly also comprise a cover *e*, a diaphragm *k* clamped between said cover and the casing *S* and a needle valve *o* secured to the diaphragm *k* for controlling communication between the valve chamber *U* and the intermediate chamber *V*. A spring *p* calibrated to withstand all pressures up to what may be termed the minimum pressure in the receiver tank *R* bears against the diaphragm *k* with one end and with its other end against a spring seat *g* which also bears against the set screw *h*.

Communication between the valve chamber *U* and the receiver tank *R* is afforded by a pipe *q* and in this pipe *q* is interposed a controlling means comprising a casing *r* in which is disposed a three-way valve *s* of a well known type. The three-way valve *s* in this instance has a transverse passage *t* extending therethrough to afford communication between the sections of the pipe *q* and a passage *u* leading from the passage *t* to afford communication between said passage *t* and a pipe *v* through which pressure fluid may be conveyed to the work. The valve *s* has a suitable lever *w* for manual operation of said valve.

The operation of the device is as follows: With the valve *J* in the position shown, atmospheric air, or pressure fluid from a lower stage cylinder, may pass freely through the ports *K* and *L* of the casing *H*, through the inlet valve *D* into the compression chamber *E*, from whence after being compressed to a higher stage, it may pass from the discharge valve *F*, and through the connection *Q* into the receiver tank *R*. If then it be assumed that the valve *s* has been rotated to such a position as to cut off all communication between the receiver tank *R* and the work as well as the valve chamber *U*, the pressure in the receiver tank *R* will be built up to that value at which it may overcome the force of the spring *f*.

After the pressure in the tank *R* reaches this value, such pressure acting against the diaphragm *d* will raise the valve *e* and permit the passage of pressure fluid into the cylinder *X* to act against the piston *Y* and thus close the valve *J* and cut off the intake

supply to the compressor cylinder *A*. The valve *J* will be thus held closed as long as the pressure in the receiver tank *R* exceeds that of the spring *f*.

If, with the pressure in the receiver tank *R* at maximum, the valve *s* be rotated to the position shown in the drawing, an adequate supply of pressure fluid of the desired higher pressure may be admitted to the work to impart to such work the initial heavy impulse required to set it in operation. At the same time while the valve *s* is in this position, pressure fluid will enter the valve chamber *U* and, acting against the diaphragm *k*, will open the valve *o* and admit pressure fluid into the cylinder *X* to hold the valve *J* closed. In this way the compressor cylinder *A* will remain unloaded until the pressure in the receiver tank *R* has been reduced to a value which will enable the spring *p* to close the needle valve *o* and again permit the spring *O* to open the valve *J*.

While two of the positions of the valve *s* have been described as well as what follows while the valve is in these positions, it will be apparent that by turning the valve *s* to a position where communication may exist only between the receiver tank *R* and the pipe *v* leading to the work, the controlling means associated with the valve chamber *U* will remain inoperative and only that controlling means associated with the valve chamber *T* will control the intake unloader valve *J*. As a result, a constant maximum pressure may be maintained in the receiver tank *R* for an indefinite period.

Although only two pressure controlling devices are illustrated in the drawings, one to operate at maximum pressure and the other at all pressures between the maximum and the minimum pressure in the receiver tank, it will be obvious that other similar devices may be included as well as suitable controlling means, such as the valve *s* to maintain constant pressures in the receiver tank *R* other than maximum and minimum as hereinbefore described.

I claim:

1. In a multi-pressure regulator, the combination of a compressor cylinder having an inlet opening and a discharge opening, a receiver tank connected to the discharge opening, an intake unloading valve controlling the inlet opening, a casing interposed between the intake unloader and the receiver tank having a pair of valve chambers, valves controlling communication between the chambers and the unloader valve, diaphragms connected to the valves exposed to receiver pressure, and springs acting on the diaphragms tending to hold the valve closed, one of said springs being adapted to yield to a lower receiver pressure than the other spring for admitting pressure fluid to the

unloader valve for closing said unloader valve and thus cut off the intake supply to the compressor cylinder.

2. In a multi-pressure regulator, the combination of a compressor cylinder having an inlet opening and a discharge opening, a receiver tank connected to the discharge opening, an intake unloader valve controlling the inlet opening, a casing interposed between the intake unloader and the receiver tank having a pair of valve chambers, valves controlling communication between the chambers and the unloader valve, diaphragms connected to the valves, springs 10 acting on the diaphragms tending to hold

the valves closed, one of said springs being adapted to withstand a greater pressure than the other spring, means for constantly exposing that diaphragm against which is exerted the greater spring pressure to receiver 20 pressure, and means for selectively exposing the other diaphragm to receiver pressure for closing the unloader valve at a minimum pressure and maintain a constant predetermined minimum pressure in the receiver 25 tank.

In testimony whereof I have signed this specification.

SNOWDEN B. REDFIELD.
